CLAIM

The ornamental design for a door frame, as shown and described.

DESCRIPTION

FIG. 1 is a perspective view of a door frame showing my new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a front elevational view thereof; and,

FIG. 7 is a rear elevational view thereof.

The door frame in FIGS. 2 through 5 is broken away for convenience of illustration.
